SCREW TYPE JACK FOR VEHICLES

Charles B. Woodworth, Port Dickinson, N. Y.

Application September 4, 1946, Serial No. 694,690

7 Claims. (Cl. 254—93)

1

The present invention relates generally to vehicle lifting jacks.

More particularly the invention is directed to certain new and useful improvements in the lifting nuts of screw type jacks.

The principal object of the invention is to provide a screw type lifting jack characterized by relative freedom from binding on the application of a load thereto.

Another object of the invention is to provide a vehicle lifting jack capable of being relatively inexpensively produced and characterized by the increased utilization of metal stampings together with the absence of fine machining operations.

A further object of the invention is to provide a vehicle lifting jack the various components of which may be expeditiously assembled in accurate relationship.

An additional object of the invention is to provide an improved nut of novel threaded construction of general application.

Other and further objects and advantages of the invention together with a clearer understanding of the precise nature thereof will become more readily apparent to one skilled in the art from a consideration of the following detailed specification taken in conjunction with the accompanying drawings in which like reference numerals refer to like parts throughout the several views and wherein:

Fig. 1 is an over-all perspective of a completely assembled jack in accordance with the present invention;

Fig. 2 is a fragmentary perspective view to an enlarged scale of the lifting nut shown in Fig. 1 in assembled condition;

Fig. 3 is a detailed perspective view of one of the toothed laminar plates forming a portion of the lifting nut of Fig. 2 and constituting an important feature of the present invention; and

Fig. 4 is a transverse cross-sectional view through the assembled lifting nut taken substantially along the line 4—4 of Fig. 2.

The present invention constitutes an improvement over the lifting jack structure as particularly disclosed in my earlier United States Patent No. 2,060,780, issued November 10, 1936.

Referring now specifically and in detail to the drawings and particularly to Fig. 1 thereof, the lifting jack in accordance with the present invention is seen to comprise generally a base 10 having an upwardly open, vertically disposed socket 11 in which is rotatably mounted the bottom end of an elongated cylindrical shaft 12 formed with a helical buttress thread 13, and having a load

2

engaging member in the form of a lifting nut 14 in threaded engagement therewith. An operating handle 16 is bifurcated at one end 17 and pivotally attached, as by means of a suitable pin 5, 18, to the top end of the shaft 12 for rotating the latter. The base 10 is generally pyramidal in form and is provided with a relatively flat bottom surface adapted to contact the ground or other supporting structure.

10 The lifting nut 14 is provided with upwardly open, horizontally aligned notches 15 at one side thereof adapted to engage a vehicle bumper or other convenient structure. It will be understood that as the operating handle 16 is moved to effect 15 rotation of the shaft 12, the lifting nut 14, which is held against rotation by the engagement of the notches 15 with the load, will be caused to move along the shaft 12 in a manner that will be apparent. For a further understanding of the 20 constructional details of the base 10 and operating handle 16, reference may be had to my earlier Patent No. 2,060,780, referred to previously.

Referring now particularly to Fig. 2, the lifting nut 14 is seen to comprise a generally U-shaped housing preferably formed as a sheet metal stamping and having a curved portion 25 adapted to be wrapped around one side of the shaft 12 in sliding engagement with the latter, and a pair of horizontally spaced arms 20, 20 extending laterally at the opposite side of said shaft. A plurality of flat laminar plates 22, 22 having substantially straight inner edges each provided with a plurality of spaced buttress teeth 24 thereon are superimposed and secured face-to-face 30 between the arms 20 in any convenient manner as by means of a vertically spaced pair of rivets 26 extending through apertures 23, 23 in the plates and similar apertures 24, 24 formed in the arms 20, 20.

40 As shown particularly in Fig. 4, the inner edges of the laminar plates 22, 22 are slightly staggered on a circular arc to provide a generally concave surface having approximately the same radius of curvature as that of the threaded shaft 12. It will be understood that, when assembled, the 45 various adjacent buttress teeth 24 are in alignment along an incline corresponding to the helix angle of the threads 13 on the shaft 12 with which they are in mesh. The assembly of laminar plates 22 thus constitutes an internally threaded 50 sector in threaded engagement with the externally threaded shaft 12 diametrically opposite to the blank sector formed by the curved portion of the housing 14 which is in sliding engagement with said shaft.

Although the particular staggered arrangement of the laminar plates 22 as illustrated in Fig. 4 may, of course, be achieved in various ways, it is preferred to assemble the plates in position between the arms 20 with the teeth 24 in engagement with the thread 13 prior to drilling the apertures 23 therein. In this way the plates 22 may be held in a clamp during this drilling operation in the same position which they will occupy after final assembly, and the drilling of all the apertures as well as the insertion of the rivets 26 may be accomplished before the clamp is removed to insure proper alignment of the parts.

In the preferred embodiment illustrated in the drawings I have disclosed a buttress type thread, as the latter is particularly well-adapted for use in those applications where the force is to be transmitted substantially axially of the threaded shaft, to avoid any tendency to burst the nut. Such a thread is also readily adapted to be produced by relatively rough machining operations and it is a feature of the invention that such an inexpensive rough thread may be employed on the shaft 12 due to the inherent tendency of the assembly of laminar plates 22, 22 constituting the lifting nut to adjust themselves to accommodate slight irregularities in the thread. This construction, for the same reason, also provides an improved fit between each individual threaded shaft and lifting bolt. A further economy in manufacture will be noted in that as indicated above, the nut is preferably assembled in position on the shaft instead of being threaded thereon after machining.

In the ordinary use of vehicle jacks of the general type described herein, the full load of the vehicle or other object to be lifted is ordinarily concentrated on the lifting hook or other load engaging device lying entirely on one side of the screw member. This concentration of the load at one side of the conventional full threaded nut inevitably tends to produce a certain amount of binding or jamming between the engaging threads at the opposite side of the nut. As will be evident from the preceding description of my improved lifting nut, his binding action is virtually eliminated by the provision of a blank sector over the non-lifting portion of the nut, and it will also be noted that this blank sector extends over considerable area to reduce the sliding frictional forces imposed upon each individual thread 13.

It is an additional important advantage of the present invention that the improved lifting nut is substantially self-lubricating over an extended period of usage. This result is brought about chiefly by the laminar assembly of the flat, toothed plates 22, 22, which may be individually soaked or otherwise coated with a suitable lubricant prior to or during assembly. After having been assembled in face-to-face relationship, a considerable portion of such lubricant is retained between the inner faces of the various plates and "bleeds" or leaks out slowly to the teeth 24, as required to replace the lubricant consumed by frictional engagement of the latter with the thread 13.

From the foregoing, it will be apparent that there has been provided a markedly improved vehicle lifting jack embodying not only improved operating characteristics, but also being capable of inexpensive and expeditious manufacture as well as freedom from maintenance attention during its useful life, and in a highly competitive

field such as that to which the present invention relates, such advantages constitute significant improvements.

Obviously numerous other modifications, alterations, and deviations from the specific structure disclosed herein, as a preferred embodiment solely for purposes of illustration, will occur to one skilled in the art without departing from the spirit or scope of the invention.

Having thus described my invention, what I claim as new and desire to secure by Letters Patent of the United States is:

1. A nut comprising a housing and a plurality of laminar plates mounted in superimposed relation therein each plate having spaced teeth along one edge and said plates being arranged to form an internally threaded sector for threaded engagement with a screw threaded shaft.

2. A nut comprising a housing, a plurality of superimposed laminar plates each having a substantially straight edge provided with spaced teeth thereon, and means mounting said plates face-to-face in said housing with their toothed edges defining a concave circular arc and with said teeth arranged in inclined alignment, to form an internally threaded sector for engagement with a screw threaded shaft.

3. In combination with a jack having a rotatable, screw-threaded shaft, a lifting member comprising a housing having a portion adapted to slidably engage one side of said shaft and spaced arms extending laterally from the opposite side thereof, a plurality of superimposed laminar plates each having spaced teeth along one edge thereof adapted to engage said shaft, and means mounting said plates face-to-face between said arms.

4. A jack comprising, a base, an elongated shaft having its lower end rotatably mounted in said base and including a screw thread extending helically along substantially its full length, means for rotating said shaft, and a lifting nut comprising a housing having a curved portion wrapped around one side of said shaft in sliding engagement with the latter, horizontally spaced arms extending laterally from the opposite side thereof, a plurality of superimposed laminar plates each having spaced teeth along one edge thereof, and means mounting said plates between said arms with said teeth in engagement with said thread.

5. A lifting jack comprising, a base having a socket therein, an elongated shaft having its lower end rotatably mounted in said socket and including a screw thread extending helically along substantially its full length, an operating handle pivotally connected to said shaft adjacent its top end for rotating the latter, and a lifting nut comprising a housing having a curved portion wrapped around one side of said shaft in sliding engagement with the latter, horizontally spaced arms extending laterally from the opposite side thereof, a plurality of flat superimposed laminar plates each having spaced teeth along one edge thereof, and means mounting said plates between said arms with said teeth in engagement with said thread.

6. A vehicle lifting jack comprising, a base having its bottom surface adapted to contact the ground and including an upwardly open socket vertically disposed therein, an elongated cylindrical shaft having its lower end rotatably mounted in said socket and including a buttress thread extending helically along a substantial portion of its length, an operating handle piv-

otally connected to said shaft adjacent its top end for rotating the latter, and a lifting nut comprising a generally U-shaped housing having a curved portion wrapped around one side of said shaft in sliding engagement with the latter, 5 horizontally spaced arms extending laterally from the opposite side thereof, a plurality of flat laminar plates each having spaced buttress teeth along one edge thereof, and means mounting said plates between said arms with said teeth in engagement with said thread.

7. A vehicle lifting jack comprising, a base having its bottom surface adapted to contact the ground and including an upwardly open socket vertically disposed therein, an elongated cylindrical shaft having its lower end rotatably mounted in said socket and including a buttress thread extending helically along approximately its full length, an operating handle pivotally connected to said shaft adjacent its top end for 15 rotating the latter, and a lifting nut comprising a generally U-shaped housing having a curved

portion wrapped around one side of said shaft in sliding engagement with the latter, horizontally spaced arms extending laterally from the opposite side thereof, a plurality of flat superimposed laminar plates each having spaced buttress teeth along one edge thereof, means mounting said plates between said arms with said teeth in engagement with said thread, and hook means on the top edges of said arms adapted to engage a part of the vehicle to be lifted.
